PORTABLE PARTITION CARTON

Henry Kondolf, New York, N. Y., assignor to
 Southern Kraft Corporation, New York, N. Y.,
 a corporation of Delaware

Application May 29, 1933, Serial No. 673,540

9 Claims. (Cl. 229—27)

My present invention relates to improvements in packages and more particularly to an improved portable partition carton designed to facilitate the handling of bottle goods. My invention also 5 comprehends a new and improved method of packaging bottled goods and the like.

The problems encountered in shipping bottled goods from the bottling plant are numerous and varied, and a package which embodies features 10 reducing the labor involved in forming the package and the cost of shipping is of extreme importance to everyone concerned. It is, of course, paramount that the bottles be protected from breakage and from having their labels defaced or 15 torn off, and the object of any bottle package is to attain this result while reducing the size of the package to a minimum.

Numerous means have been devised with these 20 ends in view, some of which afford a maximum of protection at the expense of space, while the reverse is true of others. The object of my invention is to so package bottles that they are positively protected from breakage or defacement in a package which takes up the least possible space.

Another object of my invention is to package 25 a plurality of bottles in a large carton, while each bottle is individually nested in smaller, separate sub-units of the package. Each of these smaller 30 sub-units comprises a complete case or carton holding a plurality of bottles, preferably three. Each unit may be individually removed from the larger carton and in its separate state forms a neat package which displays the enclosed bottles, 35 positively individually protects each bottle, and provides a compact unit which may be easily carried in one hand. The latter feature is important to retailing merchants in that the buyer is more readily persuaded to purchase a number of bottles 40 and provides a package to carry out.

These objects and advantages are obtained 45 through the use of foldable blanks which may be converted into package form with a minimum of effort and without the use of extraneous sealing means such as are necessary in heretofore devised packages. With my invention, the necessity for expensive sealing machinery, and sealing materials such as heavy reinforced tape or staples, etc., at the converter's plant is obviated, 50 each of the sub-units and the larger carton being self-locking and not requiring the use of extraneous sealing means. Further, each blank is formed as a single piece and thus may be produced in a single stamping or rolling operation, 55 assuring exact registry of all parts and simplifying

the manufacturing process and machinery. Another advantage is that each blank is formed from a relatively rectangular piece of material whereby there is no waste which would follow from the use of extending flaps.

The blanks are easily converted into final form and unskilled laborers may be employed, the purpose of the locking tabs thereon being apparent from a casual inspection. The smaller units are inserted within the larger carton simply 10 by sliding them endwise thereinto, no complicated operation being involved in setting the bottle units in the package. The simplicity of my invention thereby provides a large saving in converting cost while providing the other desirable advantages heretofore pointed out.

A further desirable feature of my present invention is that each of the smaller units may be removed from the carton and are immediately in a convenient form for display on the shelves, in 20 the windows and on the counters of the retail store, without requiring any change therein or further operation by the retailer. In addition, the unit serves as a convenient container in which to deliver the product.

My invention may be made of any suitable thin, 25 fibrous material, such as cardboard, single or double kraft corrugated board, or other sheet material having light weight and sufficient strength and rigidity to withstand casual 30 handling.

Other objects and advantages of my invention will be more particularly pointed out and will be apparent from the following description taken in connection with the drawings.

Referring to the drawings wherein like numerals refer to like parts throughout;

Fig. 1 is a view of one form of blank;

Fig. 2 is a view in perspective of the assembled case or portable partition carton, made from the 40 blank of Fig. 1;

Fig. 3 is a vertical section taken through the assembled case or portable partition carton of Fig. 2;

Fig. 4 is a horizontal section taken through the 45 assembled case or portable partition carton of Fig. 2 looking downward;

Fig. 5 is a front view of the upper section of a modified form of case or portable partition carton;

Fig. 6 is a partial, vertical section taken through the form of case or portable partition carton shown in Fig. 5, and illustrating the modified features thereof;

Fig. 7 is a section taken through Fig. 6 along 55

the line 7—7 and looking in the direction of the arrows; and

Fig. 8 is a perspective view of a package embodying features of my invention, showing a plurality of the smaller units as they are placed within the large carton.

Referring to the form of case illustrated in Figs. 1 to 4, the blank is shown as it emerges from a press and before it is converted into assembled form. The blank consists of a bottom wall 1 to which side walls 2 and 3 are attached along score lines 4 and 5. A top flap 6 is attached to side wall 2 along a score line 7 and has a locking tab 8 formed therein. This tab is formed by a straight diagonal cut 9 extending inward from a point near one corner of the flap to a median point, and a divergent cut 10 extending back toward the beginning of cut 9. The resultant tab is cut short of its point, forming the locking tab 8 extending from a median toward the lower corner of flap 6. Similarly, a top flap 11 is attached to side wall 3 along a score line 12 and has a locking tab 13 formed therein. This tab is formed by a straight diagonal cut 14 extending diagonally inward from a point near the upper corner of flap 11 to a median point and a divergent cut 15 extending back toward the beginning of cut 14. The resultant tab is cut short of its point to form locking tab 13 extending from a median toward the upper corner of flap 11. Thus the blank is provided with oppositely extending, interengageable locking tabs and notches.

A set of tray or compartment forming members is attached to the bottom 1 along score lines 16 and 17. These score lines are in the same straight lines as the edges of the side walls 2 and 3. End walls 18 and 19 are defined by score lines 16 and 17, respectively, and score lines 4' and 5' which are offset with respect to score lines 4 and 5 to a distance equal to the thickness of the material used in making the unit. This construction renders possible the bending of partition walls 22 and 23 into position without preventing the folding into position of walls 2 and 3. Side flaps extend from opposite sides of end walls parallel to side walls 2 and 3, side flaps 20 and 21 being joined to end wall 18, and side flaps 22 and 23 to end wall 19. Side flap 20 carries a compartment-forming flap 24 at its outer end, attached thereto along score line 25, the length of the so-formed compartment flap being slightly less than the width of the bottom wall 1. A locking notch 26 extends from a median point of member 20 toward the outer edge of the blank, the notch being of a substantially Y-shape and diverging outwardly. Flap 21 carries a similar locking notch 27 extending from a median point and diverging inwardly toward the cut separating the flap from side wall 2. Side flap 22 carries a partition flap 28 at its outer end, this partition member being defined by a score line 29 and is similar to partition flap 24. A locking notch 30, similar to locking notch 26, is formed in member 22, and a locking notch 31, similar to locking notch 27, is formed in member 23. Thus the members attached to end walls 18 and 19 are identical in structure but diagonally opposed, each flap being dissimilar to the directly opposed flap and interengageable therewith. If desired, the side flaps may be joined in the middle, that is, the notches may be formed in the middle of each side flap so as to provide two partition flaps in each side. By positioning the notches substantially in the

center of each side flap the outer end of each strip will be of a length sufficient to permit it to extend across the width of the bottom 1.

One of the side walls, in the illustration side wall 3, is formed with means to engage the necks of the enclosed bottles. This means comprises a hinged portion 32 defined by a straight cut 33 and a score line 34 parallel to score lines 5 and 12, joined by divergent cuts 35 and 36 to form a trapezoidal flap hinged at its base. A substantially rectangular portion is cut from the free end of the hinged portion, providing two tongues 37 and 38 joined by a bridge 39 adjacent score line 34.

In converting the blank of Fig. 1, the end walls 18 and 19 are bent upward normal to the plane of bottom 1. Each of a directly opposed pair of compartment-forming members is now bent normal to the end walls and its locking notch interengaged with the notch of the other member. Thus, side flaps 20 and 23 are brought together parallel to score line 5 and notches 26 and 31 are interengaged, and side flaps 21 and 22 are brought parallel to score line 4 and notches 27 and 30 are interengaged. The notches are Y-shaped or slotted to provide open ends which may be easily slipped together while the legs of the Y's provide exactly registering and firm locking means. Side flaps 20 and 22 are placed on the inside of the so-formed walls in order that compartment flaps 24 and 28 may be bent normal thereto and parallel to the end walls, thereby forming a plurality of compartments each adapted to snugly receive the large end of a bottle.

Side walls 2 and 3 are now brought normal to the bottom and top flaps 6 and 11 superimposed. The widths of the top flaps are designed to be substantially equal to the width of a capped bottle mouth, hence side walls 2 and 3 converge upwardly. By twisting the side walls, the locking notches of the top flaps are interengaged, with locking tabs 8 and 13 protected within the top wall and resting snugly against the top of the central bottle cap. The side walls tend to draw the sides of the tray snugly against the bottles, and also rest against the shoulders of the bottles and the sides of their capped mouths, while the top wall restrains them from slipping out of the compartments. The top flaps 6 and 11 need not be locked together until the package is sold by the retailer. In this event a label or seal, having advertising matter thereon may be used to close the carton. When the package is sold the retailer merely breaks the seal and locks the top flaps together by the locking notches.

The inherent stiffness of the material assures engagement of the locking flaps 8 and 13, but a small strip of gummed tape may be adhered over the top of the case to guard against the effects of careless and rough handling. The top flaps may be further secured by the use of a small quantity of adhesive. Either of these operations may be manually performed, and even if special machinery were provided for this purpose, it is apparent that such machinery would be much less complicated and expensive than would be required to set up cases by means of stitches or staples.

The bottles are further protected by the neck-engaging flap provided in side wall 3. Flap 32 is adapted to be bent upward substantially parallel to the top and bottom walls, with tongues 37 and 38 acting as spacers between the bottles and preventing them from tilting toward each other.

The tongues are narrowest at their free ends and thus may be easily slipped between the bottle necks. Bridge 39 is of such width as to engage the front of the central bottle, while the tongues 5 are of such length as to fit snugly against side wall 2. The tongues also fit snugly against the sides of the bottle necks, thereby providing a plurality of frictionally engaged edges which prevent the flap from being accidentally disengaged.

The form of case illustrated in Figs. 5 to 7 is provided with a modified flap 40. In this form the trapezoidal flap is wider at its free end while the central portion 43 is narrower, 15 providing flaring tongues 41 and 42, and the central portion 43 is left attached along a score line 44. Other features of the blank are identical to those of the first form, and the case is assembled in the same manner. Tongues 41 and 20 42 are forced between the bottle necks, the flaring ends making them harder to insert, but correspondingly harder to disengage and thus providing a further degree of safety. The central portion 43 bends downward along score 25 line 44 and engages the front of the central bottle neck, providing greater frictional contact to retain the flap, and also providing a convenient means to assist in disengaging the flap.

It is apparent that features of both flaps may 30 be interchangeable, as for example, flap 32 may have flaring tongues such as in flap 40, or flap 40 may be provided with narrowing tongues as in flap 32.

A further feature of either form of flap is that 35 when engaged, it prevents side wall 3 from skewing sideways relative to the bottles. Thus accidental disengagement of the top locking means would require the skewing of side wall 2 the full length of locking tab 6, a happening which is 40 rendered impossible due to the snug fit of the bottles and the tight, frictional engagement of the ends of the tongues against the wall.

It is evident that my case provides a maximum 45 of safety to bottled goods. Each bottle is protected by the bottom compartments and side walls and is further protected by the neck-engaging tongues. This construction meets all the present public carrier regulations. At the same 50 time a carrying package is provided which is convenient to grasp and is formed with a side opening through which the finger tips may be inserted. Also the ends of each case are open and the labels of the enclosed bottles may be seen therethrough. Another feature is that side 55 wall 2 presents a broad, plain surface which may be used to carry advertising printed matter.

Fig. 8 illustrates a large carton 50 having four of the smaller units enclosed therein, each of the smaller units being designed to enclose three bottles whereby the complete package contains a dozen bottles. It is apparent that each of the smaller units comprises a package which individually nests a plurality of bottles while occupying a space in the large carton not appreciably 60 greater than would be taken up by the bottles alone. Each case is not much wider at its base than the large ends of the bottle, and tapers upwardly to a top width not appreciably wider than the capped ends of the bottles. It is to be appreciated that the thickness of the material is 65 greatly exaggerated in the appended drawings. The side walls converge upwardly and contact the shoulders of the bottles and their capped ends. Thereby a plurality of the cases when placed in alternate reversed relation requires ma-

terially less space than is required to package a similar member of bottles in the usual carton having individual cells of the same cross-section throughout.

The large case is formed in the manner shown 5 in my copending application, Serial No. 673,541, filed May 29, 1933. The carton comprises alternate side walls 51 and end walls 52, one corner of the carton being formed by interlocking means on the end edges of one end wall and one side 10 wall. These interlocking means are more particularly described in the aforementioned application. The bottom of the carton is formed by overlapping bottom flaps hingedly attached to the walls and may or may not have interlocking 15 means in the end edges of alternate bottom flaps as described in said application. The top wall of the carton is formed by overlapping top flaps 53 and 54 hingedly attached to the side walls. Alternate top flaps 53 are plain and are first 20 folded downwardly over the open ends of the enclosed bottle cases. The other pair of top flaps are formed with interlocking notches 55 and 56 and locking tabs 57 and 58, as more fully described in said application. Top flaps 54 are 25 folded into substantially overlapped relationship over the flaps 53 and notches 55 and 56 are interengaged by skewing the side walls of the carton and sliding the locking tabs through the opposite notches. Thus the locking tabs are 30 protected within the so-formed wall and will not be accidentally disengaged. In my invention either one or both ends of the carton may be 35 formed with interlocking flaps, the purpose being to form a double thickness end wall which is easily disengaged and protects the open ends of the enclosed cases under two thicknesses of the carton material. Another useful purpose that is served thereby is that this end wall is left 40 open until the last, and the enclosed cases are slid lengthwise therethrough, and being easily disengageable, is the first portion of the carton to be opened, immediately presenting a view of the enclosed bottles through the open ends of the cases. There is thus provided a package 45 which is easily and quickly assembled and is likewise easily and quickly disassembled and the person opening such a package is not required to remove one of the single cases to ascertain the condition of the bottles or the type of beverage. 50

A further feature is that in making the end wall disengageable each smaller unit is so placed within the carton that its side wall or end walls, as the case may be, lie snugly against the side walls of the carton whereby a double thickness 55 of material protects the enclosed bottles. Further, the side walls of adjacent smaller cases provide snugly fitting double thicknesses of material between adjacent bottles. And lastly, the 60 open ends of the enclosed units are protected by the double thickness of the overlapped end flaps. It is apparent that there is no place at which less than two thicknesses of material protect the 65 enclosed bottles.

As will be evident to those skilled in the art 70 my invention permits of rearrangement of the several parts and modification of certain features thereof, and I do not intend to be limited except by the following claims which are to be broadly construed.

What I claim is:

1. A bottle case comprising a tray having individual compartments each adapted to snugly receive an end portion only of a bottle, and side walls integrally attached to the bottom of said 75

- tray adapted to snugly envelop said tray and the bottles held therein, said side walls having interengaging means on their end edges.
2. A bottle case comprising a tray having individual compartments each adapted to snugly receive the large end of a bottle, and side walls integrally attached to the bottom of said tray adapted to snugly envelop said tray and the bottles held therein, said side walls having interengageable top flaps thereon adapted to form a top wall narrower than said bottom. 5
3. A bottle case comprising a tray having compartments each adapted to receive the large end of a bottle, side walls integral with the bottom of said tray adapted to envelop said tray and bottles held therein, interengageable top flaps on said side walls forming a top wall narrower than said bottom, and a neck-engaging flap formed in one of said side walls. 10
- 20 4. A bottle case comprising a tray having compartments each adapted to receive the large end of a bottle, side walls integral with the bottom of said tray adapted to envelop said tray and bottles held therein, interengageable top flaps on said side walls, and a neck-engaging flap formed in one of said side walls, said flap being trapezoidal in shape and hinged along a line adjacent the top flap of said wall. 15
5. A bottle case comprising a tray having compartments each adapted to receive the large end of a bottle, side walls integral with the bottom of said tray adapted to envelop said tray and bottles held therein, interengageable top flaps on said side walls, and a neck-engaging flap formed in one of said side walls, said flap being trapezoidal in shape and having a central portion removed to form spaced tongues adapted to fit between the necks of adjacent bottles. 20
6. A bottle case comprising a tray having compartments each adapted to receive the large end of a bottle, side walls integral with the bottom of said tray adapted to envelop said tray and bottles held therein, interengageable top flaps on said side walls, and a neck-engaging flap formed in one of said side walls, said flap being trapezoidal in shape and cut to form spaced tongues adapted to fit between the necks of adjacent bottles and a central flap adapted to engage the front of one of said bottles. 25
7. A bottle case comprising a tray having compartments each adapted to receive the large end of a bottle, side walls integral with the bottom of said tray adapted to envelop said tray and bottles held therein, interengageable top flaps on said side walls, and a neck-engaging flap formed in one of said side walls adapted to be swung into position parallel to said bottom and form a fingerhold in the side of said case. 30
8. A package comprising a tray having compartments, bottles set within said compartments, side walls embracing said tray and bottles, self-locking flaps on said side walls interengaged to form a top wall, and a flap struck from one side wall having tongues adapted to engage the necks of said bottles. 35
9. A case comprising a tray having individual compartments each adapted snugly to receive one end of an article positioned therein, and side walls formed integral with the bottom of said tray adapted snugly to envelop said tray and the containers held therein, said side walls having interengageable top flaps therein adapted to form a top wall for said case narrower than the said bottom thereof. 40

HENRY KONDOLF.
